UNITED STATES PATENT OFFICE.

WILLIAM JOSEPH WAYLAN, OF SUTTON, ENGLAND.

PLUMBER'S SHAVE-HOOK.

SPECIFICATION forming part of Letters Patent No. 655,817, dated August 14, 1900.

Application filed March 5, 1900. Serial No. 7,393. (No model.)

To all whom it may concern:

Be it known that I, WILLIAM JOSEPH WAYLAN, a subject of the Queen of Great Britain and Ireland, residing at 284 High street, Sutton, in the county of Surrey, England, have invented an Improved Plumber's Shave-Hook, also applicable as a gage and as a marker or cutter for making washers, of which the following is a specification.

This invention relates to an improved plumber's shave-hook, which is also applicable as a gage and as a marker or cutter for making washers.

Heretofore in the use of plumber's shave-hooks of the ordinary construction considerable inconvenience is often experienced in marking and shaving any inaccessible under part or other part of a lead pipe preparatory to making a wiper-joint even when using a looking-glass therewith, and the same remark applies also to a certain extent to other constructions which have been suggested. Certain of these other constructions also have been open to objection on the score that while being excellent in use in some situations they have been exceedingly awkward to use or even useless in others. Now according to this invention I produce a plumber's shave-hook which, while applicable to all open and also awkward situations, affords absolute accuracy and expedites work. It is provided with a gage, which is useful for limiting the stroke of the hook when shaving, say, the end of a pipe, which gage is further of great utility as a circle cutter or marker, and, besides this, the gage is so constructed as to serve as a protector to the point of the shave-hook blade at will and yet is capable of being fixed out of the way when shaving a flat piece of lead.

Figure 1 of the accompanying drawings is a side elevation of my improved plumber's shave-hook, and Fig. 2 is an end elevation thereof. Fig. 3 is a view representing the tool when applied to mark or shave the end of a pipe, and Fig. 4 is an end elevation thereof. Fig. 5 represents in elevation the tool when applied to mark or cut a line parallel to the edge of a sheet of metal, such as lead. Fig. 6 shows the mode of applying the shave-hook when used as an inside gage—for example, in measuring the distance for scraping

from the edge in the angle of a leaden cistern during the making of same; and Fig. 7 is a view indicating the way the tool is used to mark or cut a circle.

The same letters of reference refer to like parts in all the figures.

I provide the shank or stem A, Figs. 1 and 2, with division-lines, say, in inches and eighths of inches, as shown, and also, if desired, divisions according to other measurements suitable for the various kinds of work most commonly occurring, and, further, I provide on the said shank a sliding gage or pointer B, formed with a more or less blunt point and made to fix, for example, by a thumb-screw C, in any desired position or to any of the aforesaid division-lines at the desired distance from the head or blade D of the shave-hook, and the radial length of the gage B is about equal to or slightly greater than the length of the blade, so as to serve as a protector or guard to the point of said blade when clamped against same. (See, for instance, Fig. 2.) It is, however, essential that the gage in other directions should be of as small dimensions as possible.

In shaving or scraping the outside of a piece of pipe—as shown in Figs. 3 and 4, for instance—the gage B is held up against the end of the pipe E and the shaving of the pipe is effected by drawing the tool toward and past the said pipe end. Stroke after stroke is taken until the whole of the end of the pipe has been scraped, and the scraping or shaving will be uniform all around. If it be merely required to mark the pipe at a certain distance from the end, the gage B is held up against the pipe end and the tool is moved around the pipe concentrically therewith, the effect of which will be that the blade D accurately makes a mark all around. The tool may also be used for marking sheet or other more or less flat lead, as indicated by Fig. 5, the gage B in this case serving as the marker and the blade being in contact with the edge of the lead F. Fig. 6 represents another way of using the tool for either marking with the point of the gage B on the side G of, say, a cistern or the like to be soldered, or the blade D is pressed, say, against the side H when drawn backward and forward to effect the scraping or shaving thereof.

In using the shave-hook as a pair of compasses or as a cutter for cutting circles in lead, leather, or the like the gage B is clamped on the shaft A, so that the points of the gage 5 B and of the blade D are at the proper distance to agree with the radius of the circle to be made. The gage is then held between the workman's fingers to hold it steady in the center and pressure is also applied to the 10 point of the blade to cause it to mark or cut the circle required, or the tool may be held by the handle A and the blade be caused to revolve on the work or the work may be caused to revolve under the tool, all as found most 15 convenient. The dotted circle K represents the mark or cut which the tool will make.

What I claim as my invention, and desire to secure by Letters Patent, is—

1. A plumber's shave-hook, comprising a 20 handle, a shank, a knife or hook secured thereto and a pointed gage adjustable on said shank, the major diameter of said gage equal to or slightly greater than the like diameter of the hook, for the purpose set forth.
2. A plumber's shave-hook comprising a 25 handle, a shank, a knife or hook secured thereto and a pointed gage adjustable on said shank, the major diameter of said gage equal

to or slightly greater than the like diameter of said hook, the least minor diameter of which 30 is greater than the least minor diameter of the gage, for the purpose set forth.

3. A plumber's shave-hook comprising a handle, a graduated shank, a knife or hook secured to the end thereof, and a pointed gage 35 adjustable along said graduated shank and having a plain outer face and a major diameter equal to or slightly greater than the like diameter of the hook, substantially as and for the purpose set forth.

4. A plumber's shave-hook comprising a handle, a shank, a V-shaped knife or hook having a convex heel end secured to said shank, and a pointed gage adjustable on the shank and having a major diameter equal to 45 or slightly greater than the like diameter of the hook whose least diameter is greater than the like minor diameter of the gage, for the purpose set forth.

In testimony whereof I have signed my 50 name to this specification in the presence of two subscribing witnesses.

WILLIAM JOSEPH WAYLAN.
